DISPLAY COVER

Jacob I. Russakov, Chicago, Ill.

Application March 25, 1933, Serial No. 662,665

1 Claim. (CL 220—82)

These improvements relate to a readily attachable and removable form of cover adapted to be positioned upon the open end portion of a box containing biscuits, crackers or other articles, whereby the receptacle may be maintained closed against dust and dirt while its contents may be exposed to the purchaser's view and be readily reached as desired. Covers for these general purposes and of the general character herein described are well known, and reference is made to my Patents Nos. 1,458,955 of June 19, 1923 and 1,511,426 of October 14, 1924 in this connection.

Display covers of this kind contain a transparent glass plate in the swinging lid. One of the objects of the present invention is to provide improved and peculiarly advantageous means for holding that glass panel or plate while permitting its ready removability as for cleaning, and means whereby such a plate may readily be inserted, both initially and should the one in use become broken. Another object is to provide peculiarly advantageous hinge for the swinging lid. Particular advantages of the constructions in these respects will appear hereinafter.

In the drawing Figure 1 is a perspective of a receptacle cover containing these improvements;

Fig. 2 is a vertical sectional view, on an enlarged scale, as on the line 2—2 of Fig. 1;

Fig. 3 is a bottom view of the lid, interiorly broken away, and showing the preferred form of panel-holding means;

Fig. 4 is an enlarged fragmentary vertical sectional view taken at the left-hand corner of Fig. 1 and also on the line 4—4 of Fig. 5;

Fig. 5 is a fragmentary substantially horizontal sectional view as on the line 5—5 of Fig. 4; and

Fig. 6 is a fragmentary vertical sectional view as on the line 6—6 of Fig. 1.

Such receptacle covers contain two main parts, namely the body 10 and the lid 11. Each of these parts is formed from thin sheet metal. The body has four depending flanges 12 adapted to fit around the outside of the open end portion of a receptacle fragmentarily shown and marked 14 in Fig. 2. From these flanges 12 the body extends inward at 15 to provide flat surfaces which serve to limit the movement of the body upon the receptacle, and they also provide surfaces against which the lid rests. Fig. 2 shows one of these parts 15 in section. Figs. 5 and 6 show that the body is open interiorly, that opening being defined by beads 16 which are formed by turning the metal of the part 15 around the wire 17, which wire 17 is to be understood as being a single wire bent into rectangular shape and then en-

compassed by the sheet metal at 16 as shown. The goods are reached through this opening defined by the continuous bead 16. The construction in that respect is old, and except for the glass-holding means and the hinge, all that I show herein may be considered old.

Turning to the lid 11, which is a rectangular sheet-metal frame, it has continuous top surfaces 18 and depending flanges 19, the lower free edges of these flanges 19 being turned around a wire 20 and 20a, which wire 20, 20a may be considered a single piece of wire bent in rectangular shape and encompassed by the metal as shown.

I mark one part of this wire 20a because that part serves as a hinge pin for the lid. That wire has been used heretofore as a hinge pin, as by the provision of hinge lugs formed of strip metal passing around the wire at exposed portions thereof between the adjacent corners of the lid. The occasion for the present improvements arises from the fact that according to older practice the hinging occurred at portions of the body and lid which are quite flexible. The movements of the lid into the open position shown in Fig. 4 brings parts together at 21 limiting the movement of 25 the lid, and the contact there causes a leverage action on the hinge pin and hinge lugs and the body is bent or deformed through careless manipulation, and the operator also has a sense of flimsiness of construction due to the springy give or 30 yield which the lid has when it comes into its open and stopped position as in Fig. 4.

I overcome these objections and provide an unusually firm and rigid hinge connection for these light-weight and yielding springy bodies 35 and lids, and also reduce the number of hinge lugs ordinarily used from three to two, and also simplify and reduce the cost of the mechanical operations of making the hinge connection, by providing a hinge lug at the corners of the lid on one side, as will be noted from Fig. 1, where the hinge lug or strap bent around the wire is marked 24. This hinge strap is secured as by a rivet upon the upper surface of the inwardly-turned part 15 of the body closely adjacent to the associated corners of the body and closely adjacent to and aligned with one side of the wire 17 and the rib 16 defining the inner opening of the body. The hinge straps also lap two of the adjacent sides of the wire and bead 16—17. The hinges are thus secured at the strongest and most reinforced portions of the body and of the lid, and substantially where the spring or yield in each is the least.

Fig. 4 shows that the hinge lug or strap 24 has 55

leaves 24a through which passes the rivet 25. It is to be noted further that these straps 24a are within the vertical projection of the lid and are not exposed when the lid is closed, as in Fig. 1, 5 and that no part of the hinge is then seen except the bent-around part 24, which is in appearance a continuation of the bead at that marginal edge.

So constructed and arranged, the hinge straps are aligned with one side each of both the body 10 wire 17 and the lid wire 20a, and the lid spans the two hinge straps as well as the side of the wire 17 which is aligned with the straps. Thus the parts stiffen and reinforce each other after 15 the manner of a unitary beam which prevents the usual deformation of the parts in the vicinity of the hinge straps.

The other feature of improvement is in the means for holding the glass panel 30, which is to be considered as of such rectangular shape and 20 dimensions as to enable it to be accommodated loosely between the opposed flanges 19 of the lid. These glass-holding means are preferably two in 25 number and are positioned at what, for convenience, may be called the upper and lower parts of the lid frame, as distinguished from the sides thereof, the hinges being at one of the sides. These two glass-holding devices are alike and a 30 description of one will suffice for both. They are both shown in Fig. 3.

30 The preferred construction is shown as a wire 32 which has eyes 33 formed at its ends and rivets 34 pass through these eyes and hold the wire 32 fixedly at its ends against the upper wall 19 of the lid frame. The rivets 34 in Fig. 1 show 35 where these rivets occur when viewed from the outside. The wire 32 is in effect bowed toward the glass 34 and preferably presses against the glass at spaced-apart places, for example at 36, 36. The springy wire 32 is tensioned toward the 40 glass, but when this spring device is made of wire and in the general form shown it is desirable to increase the spring tension holding the glass, and to that end the wire is bent away from the contact points at 36, and the catch-engaging part 45 38 is formed in the wire adapted to reach back toward the flange 19 and to be engaged by the catch 39, which is in the form of a lip pressed out of the side wall or flange 19.

Fig. 2 shows that from the rivets 34 the wire is 50 formed to extend away from the side wall or flange 19, the purpose of which is to get the contacting points as 36 so far away from the wall 19 that they will surely press upon the glass when the 55 glass is not of the full length of the hollow interior of the lid, and preferably the glass is not of that full length but is say about an eighth of an inch short thereof at each end, whereby the glass will clear the wire when the wire is in open position.

60 The construction is such that the operator presses the middle portion of the wire toward the glass to get the part 38 engaged by the catch, and

this puts additional spring pressure upon the wire, and the wire is held positively in position and develops spring pressure between the catch and each end of the wire. When it is desired to remove or insert the glass panel the wire devices are sprung free of their catches and moved into the dotted-line position shown in Fig. 3, where the tongue-like part 38 hangs upon the free edge of the lid in an out-of-the-way position and the glass can then simply be lifted away or inserted. 10 15

Particular advantages of this construction are that the wire device is held firmly at both ends, and for one thing it cannot be separated and lost. In my former practice, as indicated by the 20 patents mentioned, the wire device was mounted to swing at one end. Such a wire could easily be bent out of shape, is more or less in the operator's way, and there is the possibility of some injury because of such a wire standing up in the air while the glass is being inserted or removed. 25

The present device calls for apparently the minimum amount of movement and thought on the part of the operator and the operation is more simple and easy than in any other form of which I am aware. It is also stronger and in general more effective. Furthermore, it reinforces 30 the frame of the lid, and, together with the pressure it exerts on the glass, it produces a combination of strain-resisting elements which give the lid as a whole greater strength and rigidity. 35

Claims to the pane-retaining means shown herein are divided out hereof and are made in my copending application Serial No. 730,748, filed June 13, 1934.

I contemplate as being included in these improvements all such variations and departures from what is thus specifically illustrated and described as fall within the scope of the appended claim.

I claim:

In a display cover of the class described, the combination with a rectangular body having a horizontal flat frame-like surface and a rectangular opening therethrough, said opening being margined by a wire extending therearound and 40 the body being bent around the wire forming a bead having parallel sides, of hinge straps riveted to the body adjacent two of the corners of the opening, both hinge straps being aligned with one of the sides of the bead and each hinge strap 50 lapping one of the other adjacent sides of the bead, a lid spanning said bead and aligned hinge straps, said lid carrying a hinge pin passing through said straps at the corners of the lid, whereby the said straps are aligned with both the 55 wires of the body and of the lid and are within the vertical projection of the cover when closed and each of the parts reinforces the other in the nature of a unitary beam to prevent deformation of the parts.

JACOB I. RUSSAKOV.
